UNITED STATES PATENT OFFICE.

ALFRED HATHAWAY, OF FREETOWN, MASSACHUSETTS.

IMPROVEMENT IN BASE-BURNING STOVES.

Specification forming part of Letters Patent No. 143,693, dated October 14, 1873; application filed July 12, 1873.

To all whom it may concern:

Be it known that I, ALFRED HATHAWAY, of Freetown, in the county of Bristol and State of Massachusetts, have invented a new and valuable Improvement in Base-Burning Stoves; and I do hereby declare that the following is a full, clear, and exact description of the construction and operation of the same, reference being had to the annexed drawings, making a part of this specification, and to the letters and figures of reference marked thereon.

Figure 1 of the drawings is a representation of the bottom of my stove, and Figs. 2 and 3 are vertical sections of the stove.

My invention relates to that class of stoves known as magazine or base-burning stoves; and it consists in the novel construction and arrangement of the parts, as will be herein-after described and claimed.

In the drawings like letters in the several figures indicate corresponding parts.

A represents the base, B the outer shell, and C the top, of a base-burning stove. D represents the magazine; G, the fire-pot with grate a; and E, the ash-box. These parts may all be arranged and constructed in any of the known and usual ways, except in so far as hereinafter described. The upper end of the magazine D is surrounded by an annular flange, b, forming part of or made fast to the shell B. Through this flange pass two thumb-screws, d d, which screw into lugs or ears e e on the outer sides of the magazine D, thereby suspending the same in the stove. By means of these thumb-screws d d, the magazine is also adjusted up and down at will. The ash-box E is placed in a case, H, which is attached to or formed at the lower end of the fire-pot G. This case is also provided with external lugs f f, through which screw from underneath two screws, h h, said screws passing up through the bottom of the stove or base A, and so arranged that they will not move either up or down in said bottom. The screws h h thus support the ash-box and fire-pot, and by turn-

ing the screws they may be adjusted up and down, as desired. The turning of the screws may be accomplished in the following manner: On the lower ends of the screws are toothed wheels i i, around which passes an endless chain, m. Below the wheel i on one of the screws is a large wheel, J, extending to the edge of the base A on one side, and provided with a series of holes in its edge. By the use of a lever, p, inserted in one of said holes, the wheel is turned in either direction, thereby turning the screws h h, and adjusting fire-pot up or down, as desired.

The object of thus adjusting the magazine or fire-pot is to regulate the amount of fuel in the fire-pot, as circumstances may require, this depending upon the distance between the grate and the mouth of the magazine.

I am aware that an adjustable magazine and an adjustable fire-grate are not new, and I therefore do not claim such invention broadly.

What I claim as new, and desire to secure by Letters Patent, is—

1. The adjustable magazine D, having the outer or external lugs e e, in combination with the shell B, having the annular flange b surrounding the upper end of the magazine, and the screws d d passing through said flange and lugs, substantially as shown, and for the purpose mentioned.

2. In a base-burning stove, the adjustable case H having external lugs f f, carrying the ash-box E and fire-pot G, in combination with the base A and adjusting-screws h h, substantially as specified.

3. The means for adjusting the case, consisting of the toothed wheels i i, endless chain m, and lever-wheel J, substantially as described.

In testimony that I claim the above I have hereunto subscribed my name in the presence of two witnesses.

ALFRED HATHAWAY.

Witnesses:

W.M. F. HASKELL,
ALDEN HATHAWAY.
